UNITED STATES PATENT OFFICE.

JACOB W. NEWMAN, OF NEW ORLEANS, LOUISIANA.

COMBINATION-FASTENER.

1,312,421.

Specification of Letters Patent:

Patented Aug. 5, 1919.

Application filed November 7, 1917. Serial No. 200,808.

To all whom it may concern:

Be it known that I, JACOB W. NEWMAN, a citizen of the United States, residing at New Orleans, in the parish of Orleans and 5 State of Louisiana, have invented new and useful Improvements in Combination-Fasteners, of which the following is a specification.

My present invention pertains to combination fasteners of what is technically known 10 as the clasp-pin type; and it contemplates the provision of a clasp-pin fastener that is simple, compact and inexpensive in construction and yet is adapted to be used to 15 advantage in a wide variety of relations particularly in connection with articles of personal wear.

The invention will be fully understood 20 from the following description and claim when the same are read in connection with the drawings, accompanying and forming part of this specification, in which:

Figure 1 is a view showing the combined fastener constituting the preferred embodiment of my invention as the same appears when put to one of the uses of which it is capable.

Fig. 2 is an elevation of one side of the combined fastener.

Fig. 3 is a similar view of the other side of the fastener.

Fig. 4 is a transverse section of the fastener, taken in the plane indicated by the line 4—4 of Fig. 3, looking in the direction 35 indicated by arrows.

Similar numerals of reference indicate corresponding parts in all the views of the drawings.

My novel combination fastener is formed 40 in one piece of metal, celluloid, or any other material suitable to its purpose, and is nickel-plated or otherwise embellished, by preference, with a view to enhancing its finished appearance and better adapting it for 45 personal wear. It comprises a V-shaped body 1, having diverging legs and a wedge slot 2 between said legs, and pins 3, of hook-form, at the ends of the diverging legs of the body; the said hook-like pins being arranged 50 in planes at approximate right angles to the plane of the legs of the body as clearly shown in Fig. 1. In the present and preferred embodiment of my invention, the body 1 and the legs thereof are provided in 55 their forward sides with a groove 4. This groove, however, is merely for purposes of

ornamentation, and is not of the essence of my invention. It may, therefore, be used or altogether omitted in the discretion of the manufacturer of the fastener without involving departure from the scope of my appended claim.

It will be manifest from the foregoing that my novel combination fastener is compact, strong and neat in appearance, and that because of the wedge slot being formed between the legs that bear the hook-like pins but little material is embodied in the fastener.

In the practical use of my novel fastener, 70 the body 1 with its wedge slot 2 is adapted to receive and engage one article while the hook-like pins 3 are adapted to securely engage another article, with a view to connecting the first-named article thereto.

The foregoing will be readily understood by reference to Fig. 1 wherein the body 1 is shown as holding in its wedge slot 2 the fastening means 5 of a trousers button 6 while the hook-like pins 3 are shown in secure engagement with the broken tab 7 of a pair of suspenders. By the interposition of the fastener in the relation illustrated and described it will be manifest that connection of the broken tab 7 with the button 6 is effected in a strong and durable manner without liability of the tab being casually released from the button.

The use illustrated and described is only one of a wide variety of uses to which the 90 combination fastener is susceptible of being put. For instance it may be employed to advantage as a scarf holder, the body 1 being engaged with a button on a shirt and the pins 3 being embedded in the inner side of 95 the pendent portion of the scarf. It may also be used as a watch protector, the body 1 receiving the watch chain and the hooks or hook-like pins 3 being engaged with the material of the trousers. Other uses which 100 may be mentioned are as a cuff holder or shirt sleeve shortener, as a means of holding the turned up collar of a coat tightly closed, as a means for preventing men's belts from slipping up in front, the belt being 105 disposed in the body 1 and the pins 3 engaged with the trousers, and as a means for preventing a shirt from slipping out of trousers while assisting in the support of the trousers, a portion of the shirt being wedged 110 in the body 1 and the pins 3 being engaged with the trousers. These several uses are all

peculiar to the wearing apparel of men, but I would have it understood that the combination fastener may be put to a number of uses in connection with the apparel of women, 5 and may also be used to advantage for general purposes, office purposes, household purposes, hospital purposes, and for the care and dress of infants.

Having described my invention, what I 10 claim and desire to secure by Letters Patent, is:

As a new article of manufacture, a combination fastener of the character described, comprising a single piece of flattened suit- 15 able material, extending from its central portion forming a V-shaped body having flat diverging legs disposed edge-wise in the

same plane and presenting a wedge slot by and between the inner edges of the diverging legs, with its apex at the center of the 20 body portion and its mouth at the outer separated ends of said legs, and each leg being provided at its outer end with an integral hook-like pin extending in a plane at right angles to the plane of the legs with the end 25 of said pin extending toward the aforesaid apex, substantially as set forth.

In testimony whereof I have hereunto set my hand in presence of two subscribing witnesses.

JACOB W. NEWMAN.

Witnesses:

F. R. SAAL,

R. R. RAMOS.
